DESIGN FOR A COMBINATION KITCHEN UNIT

Salvatore Asaro, New York, N. Y.

Application August 7, 1947, Serial No. 140,759

Term of patent 14 years

(Cl. D33—19)

To all whom it may concern:

Be it known that I, Salvatore Asaro, a citizen of the United States, residing at New York, county of New York, State of New York, have invented a new, original, and ornamental Design for a Combination Kitchen Unit, of which the following is a specification, reference being had to the accompanying drawing, forming a part thereof.

The figure is a front perspective view of a combination kitchen unit embodying my new design.

The side of the combination kitchen unit not shown and the back thereof are essentially plain.

I claim:

The ornamental design for a combination kitchen unit, as shown and described.

SALVATORE ASARO.
